UNITED STATES PATENT OFFICE.

LEO KRAUS, OF CHICAGO, ILLINOIS.

DESIGN FOR A GEM-SETTING.

No. 40,006.

Specification for Design.

Patented May 25, 1909.

Application filed February 25, 1909. Serial No. 480,068. Term of patent 7 years.

To all whom it may concern:

Be it known that I, LEO KRAUS, a subject of the Emperor of Austria-Hungary, and residing at Chicago, in the county of Cook and State of Illinois, have invented a new, original, and ornamental Design for Gem-Settings, of which the following is a complete specification, reference being had to the accompanying drawings, forming part thereof.

The figure is a plan view of a gem setting showing my new design.

I claim:

The ornamental design for a gem setting, as shown.

LEO KRAUS.
